THE NORRIS PETERS CO., PHOTO-LITHO., WASHINGTON, D. C.

UNITED STATES PATENT OFFICE.

HENRY GIBBS, OF CHICAGO, ILLINOIS, ASSIGNOR TO W. D. ALLEN MANUFACTURING COMPANY, OF CHICAGO, ILLINOIS, A CORPORATION.

HOSE-NOZZLE.

SPECIFICATION forming part of Letters Patent No. 699,384, dated May 6, 1902.

Application filed February 24, 1902. Serial No. 95,223. (No model.)

To all whom it may concern:

Be it known that I, HENRY GIBBS, a citizen of the United States, residing at Chicago, county of Cook, State of Illinois, have invented 5 certain new and useful Improvements in Hose-Nozzles, of which I do declare the following to be a full, clear, and exact description, reference being had to the accompanying drawings, forming part of this specification.

Figure 1 is a view in central vertical section through a hose-nozzle embodying my invention. Fig. 2 is a detail view, in side elevation, of the outer part of the nozzle, with 15 the valve and valve-stem attached. Fig. 3 is a view in horizontal section on line 3 3 of Fig. 2. Fig. 4 is an inverted end view of the parts of the nozzle shown in Fig. 1. Fig. 5 is a detail side view of the valve-stem and valve. 20 This invention has for its object to provide a simple and effective construction of hose-nozzle whereby the water may be caused to discharge from the nozzle in a more or less solid stream or in spray form and whereby 25 also the discharge of water through the nozzle may be completely cut off.

The invention consists in the features of improvement hereinafter described, illustrated in the accompanying drawings, and particularly 30 defined in the claims at the end of this specification.

A designates what for convenience I term the "base" portion of the nozzle. This base portion A is provided upon its interior with 35 the usual screw-threads a , whereby the nozzle may be coupled to the hose, a packing ring or gasket a' being preferably placed at the inner end of the threads a . In the base portion A is formed a diaphragm a^2 , provided 40 with an orifice a^3 and with a raised valve-seat a^4 , and above the valve-seat a^4 is formed a chamber a^5 . The base portion A is formed with a tubular bore to receive the inner part of what for convenience is termed the "body" 45 portion B of the nozzle, a suitable packing ring b being preferably interposed between the body portion B and the wall of the base portion A. The body portion B is formed with an annular groove b' , into which projects 50 the end of a screw C, that passes through a

threaded hole formed in the wall of the base portion A. By this means the body portion B of the nozzle is revolvably connected with the base portion A. The inner end of the tubular body portion B is formed with one or 55 more lateral ports or perforations b^2 , two of such ports or perforations being shown in the drawings. The lower end of the tubular body portion B is interiorly threaded to receive the exteriorly-threaded portion of a tubular stem 60 D, this stem being formed with one or more ports or perforations d , corresponding to the ports or perforations b^2 in the wall of the body portion B.

As shown, the stem D carries a valve E, 65 adapted to close against the valve-seat a^4 , and, as shown, the stem D has an extension D', that connects with the body portion A in such manner as to hold the valve and stem against revolution, while permitting a longitudinal movement to such parts. Preferably the extension D' is formed as a flat web or part adapted to set within recesses a^6 in the diaphragm a of the body portion A. The valve E is preferably, although not essentially, formed separate from the stem D, 70 since by forming the valve E as a separate ring this valve may be made of rubber or like material best adapted for effectively closing 75 against the valve-seat a^4 .

From the foregoing description the operation of the nozzle will be seen to be as follows: If the parts are in the position shown in Fig. 1 of the drawings, the water will pass in the direction of the arrow into the base 85 portion of the nozzle, through the opening in the diaphragm a , into the chamber a^5 , thence through the coincident ports b^2 and d into the body portion B, from which it will discharge at the end b^4 of the nozzle. Now by turning 90 the body portion B of the nozzle the coincidence between the ports b^2 of the body portion and the ports d of the stem D may be more or less broken, as shown in Figs. 2 and 3 of the drawings, and when this is done the 95 stream of water will be broken up into spray, and thus broken up will be caused to pass with more or less of a swirling motion through the discharge end b^4 of the nozzle. When the body portion B is turned so as to cause its 100

blank wall to come opposite the ports d of the stem D , the passage of water through the nozzle will be practically cut off, although there may still be more or less leakage of water around the threads between the stem D and the body portion B . Hence it is that I prefer to provide the tubular stem D with a valve E , and it will be seen that by turning the body portion B the valve E can be caused to move downward until it firmly closes against the valve-seat a^4 , when the passage of water through the nozzle will be completely shut off.

It is obvious that the precise details of construction above set out may be varied without departure from the spirit of invention.

Having thus described my invention, what I claim as new, and desire to secure by Letters Patent, is—

- 20 1. A hose-nozzle comprising a chambered base portion, a tubular body revolvably connected to said base portion and formed with one or more lateral perforations, a tubular stem or part having one or more lateral perforations adapted to coincide with the perforations of the tubular body and means for holding said stem or part against revolution as the tubular body is revolved, whereby the coincidence between the perforations of the 25 tubular stem and of the tubular body may be varied to change the character of the stream through the nozzle.
2. A hose-nozzle comprising a base portion having an annular chamber, a tubular body 30 revolvably connected to said base portion and having a laterally-perforated part extending into said chamber, a tubular stem or part located within said chamber and having a laterally-perforated part engaging the inner end 35 of the tubular body and means for holding

said stem or part against revolution as the tubular body is revolved.

3. A hose-nozzle comprising a chambered base portion provided with a valve-seat, a tubular body revolvably connected to said base portion and having its inner end formed with one or more lateral perforations, a tubular stem or part having one or more lateral perforations adapted to coincide with the perforations of the tubular body, means for holding said stem or part against revolution as the tubular body is revolved, said stem or part being provided with a valve adapted to close against the valve-seat of the base portion.

4. A hose-nozzle comprising a chambered base portion having a valve-seat, a tubular body revolvably connected to said base portion and formed with one or more lateral perforations and with a screw-threaded inner end, a screw-threaded tubular stem comprising a valve and engaging the inner end of said tubular body and provided with one or more lateral perforations and means for holding said stem against revolution as the tubular body is revolved.

5. A hose-nozzle comprising a base portion A having a valve-seat a^4 and a chamber a^5 , tubular body B having an interiorly-threaded and laterally-perforated inner end extending into said chamber a^5 and revolvably connected 70 with said base portion, an exteriorly-threaded and laterally-perforated tubular stem D engaging said tubular body and carrying a valve adapted to close against the valve-seat a^4 and a web or part D' for holding said stem D 75 against revolution.

HENRY GIBBS.
